CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The even-length broken lines within the shaded area represent stitching that forms no part of the claimed design. The three uneven-length broken line circles within the shaded area represent eyelets that form no part of the claimed design. The uneven-length broken line shapes within the shaded area represent regions that form no part of the claimed design. The unshaded areas form no part of the claimed design. The uneven-length broken lines immediately adjacent to the shaded area represent bounds of the claimed design and form no part thereof. The broken lines depicting the remainder of the shoe form no part of the claimed design.
